[57] **CLAIM**

The ornamental design for a socer shoe body, as shown and described.

DESCRIPTION

FIG. 1 is a left side elevational view of a socer shoe body showing my new design;

FIG. 2 is a right side elevational view thereof;

FIG. 3 is a front elevational view thereof;

FIG. 4 is a rear elevational view thereof;

FIG. 5 is a top plan view thereof;

FIG. 6 is a bottom plan view thereof.

The characteristic feature of my new design resides in the stitching patterns on the toe and counter as shown.
